UNITED STATES PATENT OFFICE

ARTHUR E. CALVIRD, OF FARMINGTON, MISSOURI

TOBACCO CAN

Application filed January 13, 1930. Serial No. 420,427.

The present invention relates to tobacco cans and has for its principal object to provide a match container therein.

A further object of the invention is to provide a match container carried at the bottom of the can and which may be moved upwardly into the can as the tobacco is consumed so as to retain the unused tobacco adjacent the open end of the can.

10 A further object is to provide an article of this character of a simple and practical construction, neat and attractive in appearance, which is relatively inexpensive to manufacture and otherwise well adapted for the purpose for which the same is intended.

Other objects and advantages of the invention reside in the special construction, combination and arrangement of the various elements forming the invention as more fully 20 hereinafter described and claimed, reference being had to the accompanying drawings forming part hereof, wherein like numerals refer to like parts throughout, and in which:

25 Figure 1 is a side elevational view,
Figure 2 is a vertical sectional view along a line 2—2 of Figure 1,

Figure 3 is a transverse sectional view along a line 3—3 of Figure 1, and

30 Figure 4 is a perspective view of the match container.

Referring now to the drawings in detail, the numeral 5 designates a tobacco container of conventional construction which is open at each end and provided with hinged covers 35 6. The container is adapted for holding a quantity of tobacco 7 which is preferably placed therein within a paper wrapper or package 8.

40 A match container 9 is carried within the bottom end of the container and is constructed substantially in the form of a tray invertedly arranged within the container and secured in position by the lower cover 6. The walls 10 of the match container are relatively low so as to form the match holder of relatively shallow construction and thus occupy relatively small space within the container.

One side of the walls 10 are cut away as 50 shown at 11 to prevent interference therewith by the hinge 12 of the cover.

The match holder is adapted to fit snugly within the walls of the container so as to be retained in position therein by frictional engagement when the tobacco has been partly consumed. After the tobacco is consumed the 55 match holder 9 is moved upwardly into the container thus maintaining the level of the unused tobacco adjacent the upper portion of the container.

As the tobacco is consumed the space below 60 the match holder will become enlarged and thus serve to accommodate additional matches, or other objects if desired.

It is obvious that my invention is susceptible to various changes and modifications in 65 construction without departing from the spirit of the invention or the scope of the appended claims, and I accordingly claim all such forms of the device to which I am entitled.

Having thus described my invention, what I claim as new is:

1. A tobacco container of the class described open at each end, covers for each end of the container and a match holder positioned in one end of the container and movable longitudinally thereof.

2. A tobacco container of the class described open at each end and provided with covers at each end and a match holder positioned in one end of the container having its walls in frictional engagement with the walls of the container whereby to retain the match holder in a predetermined position longitudinally of the container.

3. A tobacco container of the class described having each end open, covers hingedly carried at the ends of the container for closing the same and a match holder carried at the lower end of the container and comprising a tray invertedly arranged and movable upwardly of the container as the tobacco is used therefrom, said holder having its walls in frictional engagement with the walls of the container for securing the holder in a predetermined position.

In testimony whereof I affix my signature.

ARTHUR E. CALVIRD.
